No. 630,582.

Patented Aug. 8, 1899.

R. BIGLEY.

HEATER.

(Application filed July 31, 1897. Renewed Mar. 3, 1899.)

(No Model.)

UNITED STATES PATENT OFFICE.

RICHARD BIGLEY, OF TORONTO, CANADA.

HEATER.

SPECIFICATION forming part of Letters Patent No. 630,582, dated August 8, 1899.

Application filed July 31, 1897. Renewed March 3, 1899. Serial No. 707,665. (No model.)

To all whom it may concern:

Be it known that I, RICHARD BIGLEY, manufacturer, of the city of Toronto, in the county of York, in the Province of Ontario, Canada, have invented certain new and useful Improvements in Heaters, of which the following is a specification.

My invention relates to improvements in hot-water heaters; and the object of the invention is to design a simple and cheaply-constructed form of heater in which the water may be rapidly heated for distribution; and it consists, essentially, of a heater comprising a series of circular coils connected together by nipples and having a central oblique diaphragm so arranged as to direct the water below and around the coil before it ascends to the next coil, the bottom coil being of special construction and the parts being otherwise arranged as hereinafter more particularly explained.

Figure 1 is a perspective view of a hot-water heater provided with my improvements. Fig. 2 is a sectional plan through the upper portion of the base-section. Fig. 3 is a sectional plan through one of the coils. Fig. 4 is a perspective detail of a coil provided with an alternative form of nipple.

In the drawings like letters of reference indicate corresponding parts in all the figures.

A is the ash-pit casing, which is provided with an internal flange.

B is the bottom section, which is provided with an annular water-space b, extending all around the fire-pot.

C is the return-pipe leading into the annular water-space b.

D is one half of the inclosing casing for the water-coils, which rests on a flange b', extending around the lower section B, and d is a flange extending around the top of the section B, and d' are bolt-holes by which the half casing D is connected to the opposite half (not shown) by bolts.

E is the smoke-pipe.

B' is the outermost ring of the lower section, which forms an upper extension to the water-space b.

B² is the inner ring of the section B, which is connected to the ring B' by passage-ways b², and B³ is the circular water-space at the center of the section, which is connected with

the inner ring B² by the passage-ways b³. It will be noticed that the passage-ways b² are located midway between the passage-ways b³, so as to provide for increased circulation, and thereby allow the water to be heated rapidly.

B⁴ is a ring-boss formed in the center of the lower section B and internally threaded.

E are the circular coils, which consist of outer rings E', inner rings E², connected to the outer rings E' by the passage-ways e', inner ring E³, connected to the ring E² by the passage-ways e², intermediately situated to the passage-ways e', and central water-space E⁴, connected to the ring E³ by two diametrically-situated passage-ways e³, intermediately situated relatively as to the passage-ways e². The central water-space E⁴ is divided into an upper and lower portion e⁵ and e⁶ by an oblique diaphragm e', extending from the bottom of the center water-space to the top at the opposite side, as shown.

The coil E is provided with top and bottom ring-bosses E⁵ and E⁶, respectively, which are internally threaded.

F are screw-nipples which connect the ring-bosses of one coil or section to that of the adjacent section.

G is the flow-pipe leading from the center of the uppermost coil.

It will be seen by the way the passage-ways e', e², and e³ are arranged that the circulation of the water is retarded, and this, of course, in practice permits of the rapid heating of the water.

The circulation of the water is through the lower section in the direction indicated by arrow to the central water-space B³, up through the nipples F, beneath the diaphragm e', outwardly in the direction indicated by arrow through the passage-ways to one side of the coil, and around and inwardly in the direction indicated by arrow through the passage-ways to the upper side of the oblique diaphragm, then up through the nozzle, whence the course is exactly the same as hereinbefore premised through the other coils.

It will be noticed that the flow-pipe, of which really the nipples connecting the coils are a continuation, is located in the center of the heater, and consequently the heat from the furnace is imparted thereto as well as to the coils around which the heat circulates

and serves to rapidly and quickly heat the water to the desired temperature.

In Fig. 4 I show an alternative form of nipple. The ring-bosses are formed substantially as hereinbefore described and internally threaded, and the nipple is externally threaded and screwed directly through the coil. The nipple itself is provided with a central oblique diaphragm 3 and openings 4 at 5 one side above the diaphragm and an opening 5 at the other side below the diaphragm. The lower end of the nipple is reduced in size and externally threaded, while the upper end has an annular shoulder formed above, which has 15 an internal thread which is designed to receive the reduced end of the nipple above.

Although I show my coils as applied to a heater where the heat is received directly from the fire, it will of course be understood 20 that the same principle might be used in radiators.

It will be noticed in my heater that the outside periphery of the coils is situated some distance from the jacket, and consequently 25 the products of combustion are allowed a free passage to the outside of the coils, which is not the case in any other construction of the circular-coil heater of which I am aware.

What I claim as my invention is—

30 1. In a heater, a coil comprising a plurality of annular water-spaces, passage-ways connecting the annular water-spaces alternately arranged, so that each passage-way of one water-space is opposite the wall of the adjacent water-space, ring-bosses formed on each side of the central water-space, a diaphragm extending obliquely from one side to the opposite side and suitable flow and return pipes or nipples connected to the bosses as and for 35 40 the purpose specified.

2. In a heater, in combination, the lower fire-pot section having an annular substantially vertical peripheral water-space provided with an upper inwardly-extending annular 45 water-space having a rounded inner periphery, an intermediate annular water-space and

circular central water-space, passage-ways connecting the water-spaces alternately arranged, so that each passage-way of one water-space is opposite the wall of the adjacent water-space and an upwardly-extending boss and a suitable central flow-pipe and peripherally-placed return-pipe, substantially as described.

3. In a heater, in combination a plurality of coils each comprising a plurality of annular water-spaces, passage-ways connecting the annular water-spaces alternately arranged so that each passage-way of one water-space is opposite the wall of the adjacent water-space, 60 ring-bosses formed in the center of each coil, nipples connecting the bosses and forming the sole support of the completely-separated coils from end to end and the diaphragm extending obliquely in the center of each coil between the bosses, substantially as described.

4. In a heater, in combination a plurality of coils each comprising a plurality of annular water-spaces, passage-ways connecting the annular water-spaces alternately arranged so 70 that each passage-way of one water-space is opposite the wall of the adjacent water-space, ring-bosses formed in the center of each coil, nipples connecting the bosses and forming the sole support of the completely-separated 75 coils from end to end, the diaphragm extending obliquely in the center of each coil between the bosses, a bottom water-section of greater diameter than the top coils and a casting also of greater diameter than the top coils 80 resting on the bottom section formed in two halves divided vertically diametrically and connected together by flanges whereby the products of combustion are carried through the top of the fire-pot section completely 85 through and around the opposite periphery of the top coils, substantially as described.

RICHARD BIGLEY.
